His Attorney.

UNITED STATES PATENT OFFICE.

WILLIAM K. KEARSLEY, JR., OF SCHENECTADY, NEW YORK, ASSIGNOR TO GENERAL ELECTRIC COMPANY, A CORPORATION OF NEW YORK.

X-RAY APPARATUS.

Application filed January 31, 1922, Serial No. 533,070. Renewed October 14, 1927.

The present invention relates to the regulation of X-ray devices and comprises in particular a device for so controlling an X-ray tube that an X-ray output of substantially 5 constant radiographic effect is obtained even though the supply voltage varies materially.

In a prior Patent No. 1,653,102, issued December 20, 1927, I have described a regulating device whereby the operating current of 10 an X-ray tube is maintained substantially constant under varying operating conditions. In an X-ray apparatus supplied with current for heating the cathode derived from the same source as the current for generating X- 15 rays, the operation of my prior regulator maintains the current through the X-ray tube substantially constant even though the supply voltage should increase. However, the increase of voltage impressed on the X- 20 ray tube results in the production of X-rays of greater penetrability. Hence, during ordinary use of the tube, for example, in diagnostic work, the effect on a phonographic surface may be increased by an increase of 25 supply voltage even though the operating current and consequently the quantity of X-rays remains substantially unchanged.

My present invention comprises an improved regulator provided with means whereby 30 the current through the tube is automatically varied inversely with any change of applied voltage to obtain a substantially constant radiographic effect.

The accompanying drawing diagrammatically illustrates one embodiment of my invention.

The X-ray tube 1 is supplied with electric current from the high tension secondary of a 40 transformer 2 by the conductors 3, 4. The X-ray tube has been illustrated somewhat conventionally as its construction is well understood, see for example, U. S. patent to Coolidge 1,326,029. The cathode filament (not shown) is supplied with current by the low tension secondary of a transformer 5, the 45 transformer primary receiving current from a supply source represented by the conductors 6, 7, which also furnishes current to the primary of the transformer 2. Included in the supply circuit 8, 9 of the transformer 5 are 50 make and break contacts 10, 11, the former contact 10 being mounted on a magnetic armature 12. The armature 12 is caused to vibrate by an electromagnet 13, which has

two windings 14, 15, the winding 14 being 55 connected across the conductors 6, 7 in series with an inductance coil 16, and the winding 15 being connected by the conductors 17, 18 in series with the coils 19, 20 of the transformer 2.

The magnetic effect of the coil 14 will vary with the variations of voltage of the supply source, and hence also varies directly with the voltage impressed on the electrodes of the X-ray tube as the voltage of the secondary of the transformer is proportional to the voltage of the primary. The effect of coil 15 will vary with the variations of current through the X-ray tube. Preferably these two coils are so proportioned that with a substantially constant given supply voltage the relative periods of make and break of the contacts 10, 11 will be of such relative duration that the current through the X-ray tube will remain substantially constant. The voltage coil 14 is 70 wound to assist the current coil 15 so that an increase of voltage lengthens the period of break reducing the cathode heating current and conversely a decrease of supply voltage shortens the period of break, increasing the cathode heating current. As the low tension heating current determines the electron emission of the cathode and the electron emission in turn determines the current through the X-ray tube, an increase or decrease of heating 75 current, as a consequence, will cause an increase or decrease of the high tension current. Preferably the ampere turns of the two windings are so chosen that the current through the X-ray tube will vary inversely in proportion to the square of the line voltage thereby producing nearly a constant effect on a photographic film or plate regardless of supply voltage changes.

The effect of the winding 14 is magnified 95 by the reactance 16, which is preferably operated at a point on the saturation curve where the current increases rapidly with increase of voltage.

What I claim as new and desire to secure 100 by Letters Patent of the United States, is:

1. An X-ray apparatus for incandescent cathode X-ray tubes comprising a main operating circuit, a transformer having a primary winding connected thereto, a cathode heating circuit, make and break contact in said heating circuit, and electromagnetic means for operating said contacts including a winding 105

responsive to the current in the secondary of said transformer and a winding responsive to the voltage of said main circuit.

2. An X-ray apparatus comprising the combination of an X-ray tube having an anode and a cathode adapted to be heated by passage of electric current, a circuit connected to supply heating current to said cathode, a main supply circuit, and a vibrating regulator responsive to both the current traversing said tube and voltage of said main supply circuit to regulate the heating current in said first circuit to produce a substantially predetermined radiographic effect from said X-ray tube in a given time.
3. An X-ray apparatus comprising electric transforming means comprising a step-up winding and a step-down winding electrically connected to each other, and a vibrating regulator having voltage-varying means in circuit with said step-down winding and having an operating coil responsive to current in said step-up winding and another coil connected to be responsive to voltage variations in said transforming means.

4. An X-ray apparatus comprising a step-up transformer, a step-down transformer, the secondaries of said transformers being electrically connected, and a vibrating regulator having a make and break contact in one of the circuits of said step-down transformer, and having one operating coil in series with a secondary winding of said step-up transformer and another operating coil connected in shunt to a primary winding of said step-up transformer.

5. In combination with a thermionic device, means for furnishing a main load current therefor, means for furnishing an auxiliary

current for heating the cathode of said device and means whereby the current in said auxiliary current may be varied, said means comprising a winding connected to be responsive in its effect to variations of the amperage of said load current and a winding responsive in its effect to variations of the voltage of said load current, said means being operative to maintain the energy output of said device substantially constant.

6. An apparatus for operating a thermionic X-ray device from a variable energy supply source, comprising a main load circuit, an auxiliary cathode heating circuit, and a regulator for maintaining the current of said auxiliary circuit at such value that an X-ray output of substantially constant radiographic effect will be produced, said regulator having control members respectively responsive to the current value and voltage of said load circuit and means cooperating with said regulator whereby the current in said auxiliary circuit will be varied inversely with changes of either characteristic of said load current.

7. The combination of a thermionic X-ray tube, a circuit for supplying a high potential load current therefor, a circuit for furnishing a cathode heating current, a regulator for said heating circuit, said regulator producing a substantially constant radiographic effect in the X-ray output of said tube, said regulator having windings respectively responsive to variations of amperage and voltage of said high potential load circuit and a reactance winding connected in series with the voltage-responsive winding.

In witness whereof, I have hereunto set my hand this 30th day of January, 1922.

WILLIAM K. KEARSLEY, JR.

CERTIFICATE OF CORRECTION.

Patent No. 1,698,334.

Granted January 8, 1929, to

WILLIAM K. KEARSLEY, JR.

It is hereby certified that error appears in the printed specification of the above numbered patent requiring correction as follows: Page 1, line 23, for the word "phonographic" read "photographic"; and that the said Letters Patent should be read with this correction therein that the same may conform to the record of the case in the Patent Office.

Signed and sealed this 19th day of February, A. D. 1929.

(Seal)

**M. J. Moore,
Acting Commissioner of Patents.**
